SUCTION APPARATUS

Francis L. Barstow, Springfield, Mass., assignor to
New York Belting & Packing Company, Passaic,
N. J., a corporation of New York

Application February 11, 1933, Serial No. 656,239

12 Claims. (Cl. 92—52)

My invention relates to suction apparatus, and more particularly to suction rolls for use in paper making machinery for extracting moisture from pulp on a porous conveyor, such as a felt belt.

5 In the manufacture of paper it is customary practice to convey the pulp from the Fourdrinier wire or other sheet forming devices through pressure rolls, commonly called presses, to drying drums for the extraction of liquids. Such press 10 rolls are arranged in pairs, the upper roll usually having a polished continuous surface. Various metals, rubber, wood, stone and composite material may be used for such rolls. The lower roll is frequently provided with means for removing 15 moisture from the pulp by the application of a vacuum.

One form of lower pressure roll which is frequently used is a metal shell supported at its ends by heads resting in bearings. The shell is 20 provided with perforations which rotate past a stationary suction box. The suction box is disposed adjacent the area of engagement between the upper and lower rolls so that the suction is applied to the area of the lower roll in cooperative engagement with the upper roll at any time. The outer cylindrical surface of the shell is preferably provided with a layer of relatively soft material such as rubber. The thickness of this 25 coating may be of the order of one inch. This outer surface is also perforated so that the pulp carrying conveyor disposed between the two rolls is subject to a vacuum for withdrawing liquids from the pulp on the conveyor. The porous conveyor belt is frequently driven by the bite of the 30 rolls. This also provides pressure for forcing the liquids from the pulp and for compacting the pulp.

Heretofore considerable difficulty has been encountered in the manufacture of perforated coated press rolls. The shell proper has usually been 40 made of metal which is perforated with a great many smaller holes of the order of $\frac{1}{16}$ of an inch in diameter on circumferential and widthwise centers of the order of $\frac{1}{8}$ to $\frac{1}{4}$ of an inch. The 45 drilling of such holes offers no particular difficulty. However, when the covering is applied, particularly in the case of a rubber covering, it is in the form of a continuous sheet which extends over and closes the openings in the underlying metal. Thereafter it is necessary to separately drill the openings in the covering. The 50 problem of securing registry between the openings in the covering and those in the underlying metal of the shell is extremely difficult, even in the manufacture of new rolls. Where it is de-

sired to recover a used roll, the problem of securing registry is much more difficult. In many instances it is desired to recover the roll at a factory or plant other than that of the original manufacturer of the roll. In such a case it is 60 first necessary to secure from the original manufacturer of the roll an index of the drilling of the openings in the metal roll or to laboriously plot them. Because of these conditions the paper manufacturer usually takes the roll out of service 65 and ships it to the manufacturer.

I provide suction apparatus in which the coating is separable from the metal shell so that the replacement of the coating does not take the metal shell out of service for a great length of 70 time, nor does it require that the shell be sent to a specially equipped factory. By providing the coating in the form of a belt having a length considerably in excess of the circumference of the roll and by providing perforations in the belt and 75 then running the belt between the pulp conveying belt and the metal shell as the latter rotates, suction is effectively applied to the pulp. Preferably the openings in the belt at the shell engaging surface are of greater diameter than are the openings in the shell. If desired the outer ends of 80 the shell openings and the inner ends of the conveyor openings may be flared. Also the number of openings in the belt may be in excess of the number of openings in the shell. In either or 85 both cases a sufficient number of the belt openings will be in registry with the shell openings to insure the application of a vacuum to the porous pulp conveyor which is momentarily supported by the lower press roll.

90 Provision is made for tensioning and guiding the perforated belt. Provision is also made for cleaning the porous belt of particles of pulp or other material which may be carried by it.

The accompanying drawing illustrates a present 95 preferred embodiment of my invention, in which

Figure 1 is a diagrammatic view, partially in elevation and partially in section, of the suction apparatus embodying my invention;

Fig. 2 is a cross sectional view of a portion of 100 the shell and perforated belt;

Fig. 3 is a broken plan view of a portion of the shell and perforated belt; and

Fig. 4 is an elevational view of adjusting and 105 guiding apparatus for the perforated belt.

Referring to the drawing, a porous conveyor belt 1, generally of felt, is advanced by driving rolls 2 for engaging a partially dried sheet of pulp 4. The porous conveyor belt 1 and the sheet 4 are fed between an upper or top press roll 5 and 110

a lower or bottom press roll 6 for removing liquids, principally water, from the sheet 4. The liquids are removed by the combined pressing action of the rolls 5 and 6 and by the application of vacuum to the belt 1 as it bears against the roll 6. The vacuum is applied by providing a shell 7 of the roll 6 with a plurality of perforations 8 throughout its circumference. The openings 8 are of the order of $\frac{1}{16}$ of an inch in diameter 10 on circumferential and widthwise centers of the order of 4/10 to 5/10 of an inch. It is to be understood that these values are exemplary and are not to be considered limitations of the invention as different manufacturers use different sizes and 15 spacings of openings. The shell 7 is mounted in brackets 9 by stub shafts 10 extending from heads 11. One of the heads may be provided with a gear 12 for rotating it. The conveyor belt 1 is advanced by the bite of the rolls 5 and 6.

20 A stationary suction box 14 is mounted within the shell 7 by supporting arms 15 which may extend outwardly from one or both of the stub shafts 10. A flexible pipe line (not shown) may be attached to one of the stub shafts for applying 25 vacuum to the interior of the suction box 14 through a channel or channels in the arm or arms 15. The details of these connections are well known in the art, for which reason a full description is omitted from the present specification.

30 For providing a cushioning surface between the conveyor belt 1 and the metallic surface of the shell 7, which is often of bronze, I provide a perforated belt 16 of flexible material such as rubber. Where rubber is used as the material for 35 the belt 16 it should be cured and may be of the same general characteristics as rubber covers now used on such rolls. However, due to the elimination for the need of permanently attaching the rubber to the metal of the shell 7 the 40 thickness is materially reduced. This also eliminates the need for specially bonding the coating surface to the shell 7 which has heretofore been a very difficult and costly operation. The rubber coatings permanently attached now normally 45 used are of the order of $1\frac{1}{16}$ inches in thickness including the bonding layers and the outer cushioning layers. The belt 16 may be of the order of $\frac{1}{16}$ of an inch in thickness which is a common thickness for a cushioning rubber. Openings 17 50 are provided in the belt 16 for cooperation with the openings 8 in the shell 7. To this end the outer ends 18 of the openings 8 may be flared to cooperate with flares 19 at the inner ends of the openings 17. The sizes and spacings of the openings 17 may be the same or vary slightly from 55 the sizes and spaces of the openings 8 as the provisions of the flaring ends of these sets of openings insures that, regardless of the relative positions of the shell 7 and the belt 16, there will be 60 a sufficient number in contact to insure the application of a vacuum in that portion of the belt 16 outside of the suction box 14.

Because of the tendency for slippage between the shell 7 and the belt 16 owing to the driving 65 force transmitted to the porous conveyor belt 1, it is desirable to tension the belt 16 and insure that it has a sufficient frictional engagement with the shell 7 to prevent slippage. This may be accomplished by causing the belt 16 to 70 engage the surface of the shell 7 throughout a large angle, an engagement of substantially 240° being shown in Fig. 1. Also a tensioning roll 20 may be mounted in brackets 21 having adjustment screws 22 and 24 for tensioning the belt 16. 75 Flanges 25 are provided at the ends of the roll

20 to prevent the belt 16 from running off the roll.

In order to remove particles of pulp, lint, and the like, from the belt 16, a spray line 26 may be provided for washing the belt. An air blast 80 may be used in lieu of the spray 26. The spray 26 is preferably placed internally of the belt 16 so as to wash the refuse outwardly through the openings 17 and thus rid the belt of it. A catch 85 basin 27 may be provided for removing the wash water and the refuse.

Referring to Fig. 4 for positioning the belt 16 with respect to the shell 7, I may provide positive guiding means in lieu of the tension roll 20 shown in Fig. 1. To this end I provide a guide finger 28 which is stationarily mounted on a bed 29. An adjustable finger 30 on the bed 29 is controlled by a screw 31 extending through a boss 32. By adjusting the relative positions of the fingers 28 and 30 various widths of belt may 95 be guided. For positioning the bed 29 relative to the shell 7, I provide a base 34 having a way 35 for the bed 29. A screw 36 operated by hand-wheel 37 enters a threaded bore 38 in the bed 29 for adjusting it laterally with respect to a 100 boss 39 on the base 34.

If desired, the guiding apparatus shown in Fig. 4 may be used in conjunction with the tensioning roll 20, or the tensioning roll 20 may be given lateral adjustment.

With the apparatus of the present invention the need for accurate drilling of openings in a rubber or other soft covering for a suction roll is eliminated, since the covering of the present invention is in the form of a belt as distinguished 110 from a permanent covering vulcanized or otherwise fastened to the shell 7. The dispositioning of the perforations 17 in the belt 16 is such that a sufficient number of them will be in a co-operative contact with perforations 8 at the 115 suction box 14 to effectively withdraw the moisture from the belt 1. This construction also eliminates the need for removing the shell 7 from a paper mill and transporting it a considerable distance to have it recovered.

While I have shown and described the present preferred embodiment of the invention in connection with paper machinery, it is to be understood that the invention may be otherwise utilized and embodied within the spirit of the invention and the scope of the appended claims.

Having thus described my invention, what I claim and desire to protect by Letters Patent is:

1. In suction apparatus, the combination with a movable surface having outwardly flared openings therein, and means for applying a condition of vacuum to the inner ends of said openings, of a separable cushioning layer having perforations flaring outwardly toward the flared perforations in said surface whereby a condition of vacuum is transmitted through said surface and cushioning body without requiring perfect registry of the openings therein.

2. In suction apparatus, a support having a plurality of openings extending therethrough, 130 means for applying a condition of vacuum to certain of said openings, and a separable cushioning body engaging a portion of the surface of said support, said cushioning body having openings extending therethrough of sufficient number and 135 shape to transmit the condition of vacuum from the support to the outer surface thereof without requiring precise registry of the openings in said support and cushioning body.

3. In suction apparatus, a support having a 140

- plurality of openings extending therethrough and being flared at their outer ends, means for applying a condition of vacuum to certain of said openings, and a separable cushioning body engaging a portion of the surface of said support, said cushioning body having openings flared at their inner ends extending therethrough and of sufficient number and shape to transmit the condition of vacuum to the outer surface thereof without requiring precise registry of the openings in said support and cushioning body. 5 80
4. The combination with a perforated metallic press roll, of a perforated rubber cushioning belt for transmitting a condition of vacuum from the interior of the roll to the exterior surface of the cushioning belt. 10
5. The combination with a perforated bottom press roll, and means for applying a condition of vacuum to at least a portion of the interior of said roll, of a separable, perforated rubber cushioning belt directly engageable with a portion of the outer surface of said roll for carrying material traversing a pair of press rolls and applying a condition of vacuum thereto. 15
6. The combination with a perforated press roll for a paper machine, and means for applying a condition of vacuum to at least a portion of the interior of said roll, of a separable, perforated rubber cushioning belt directly engageable with a portion of the outer surface of said roll for carrying material traversing a pair of press rolls and applying a condition of vacuum thereto. 20
7. A belt for a suction device having a plurality of openings therein, the openings at one face of the belt occupying a larger area of the belt than at the opposite face. 25
8. The combination with a perforated press
- roll, and means for applying a condition of vacuum thereto, of a perforated rubber cushioning belt having openings for cooperation with the perforations in said roll for transmitting the condition of vacuum, and means for tensioning and guiding the belt. 30
9. The combination with a roll having perforations for the transmission of a condition of vacuum, and a separable conveyor having vacuum transmitting perforations for cooperation with those of the roll, of means cooperating with a portion of said conveyor separated from said roll for removing foreign matter. 35
10. The combination with a roll having perforations for the transmission of a condition of vacuum, and a separable conveyor having vacuum transmitting perforations for cooperation with those of the roll, of a spray for cooperating with a portion of said conveyor separated from said roll for removing foreign matter. 40
11. The combination with a roll having perforations for the transmission of a condition of vacuum and a separable conveyor having vacuum transmitting perforations for cooperation with those of the roll, of a spray disposed internally of a position of the conveyor separated from said roll for removing foreign matter. 45
12. The combination with a roll having perforations for the transmission of a condition of vacuum and a separable conveyor having vacuum transmitting perforations for cooperation with those of the roll, of a spray disposed internally of a portion of the conveyor separated from said roll for removing foreign matter, and a catch basin for conveying the washings away from the machine. 50
